UNITED STATES PATENT OFFICE.

HUBERT KRANTZ, OF NEW YORK, N. Y.

DESIGN FOR A MOLDING FOR ELECTRICAL CONDUCTORS.

SPECIFICATION forming part of Design No. 31,193, dated July 11, 1899.

Application filed June 15, 1899. Serial No. 720,707. Term of patent 7 years.

To all whom it may concern:

Be it known that I, HUBERT KRANTZ, a citizen of the United States of America, residing in the borough of Brooklyn, city of New York, 5 State of New York, have invented a Design for Moldings for Electrical Conductors, of which the following is a specification.

My design for a molding for electrical conductors is shown in the accompanying drawing, which is a perspective view of a portion of such molding.

A is a flat plate with flanges d a , and B is a channeled plate fitted to the flanged plate. This plate B has its channels b b' b^2 alternating in reverse.

The essential feature is the flanged plate in conjunction with the channeled plate.

I claim as my invention—

The design for a molding for electrical conductors, herein shown and described.

In testimony whereof I have signed my name to this specification in the presence of two subscribing witnesses.

HUBERT KRANTZ.
